(57) **CLAIM**

The ornamental design for a density altitude reticle, as shown and described.

DESCRIPTION

FIG. 1 is a front view of an embodiment of a density altitude reticle according to the present invention.

FIG. 2 is a rear view of the density altitude reticle of FIG. 1.

FIG. 3 is a left side view of the density altitude reticle of FIGS. 1-2, the right side view being a mirror image of the left side view.

FIG. 4 is a top plan view of the density altitude reticle of FIGS. 1-2, the bottom plan view being a mirror image of the top perspective view.

FIG. 5 is a front view of an embodiment of a density altitude reticle according to the present invention.

FIG. 6 is a rear view of the density altitude reticle of FIG. 5.

FIG. 7 is a left side view of the density altitude reticle of FIGS. 5-6, the right side view being a mirror image of the left side view; and,

FIG. 8 is a top plan view of the reticle of FIGS. 5-6, the bottom plan view being a mirror image of the top plan view. The dashed lines on the outer circular edges of FIGS. 1, 2, 5 and 6 illustrate an outer edge of the density altitude reticle according to the present invention and is intended to be a part of the claimed invention. These dashed lines on the outer circular edge are similar shown in alternative views in FIGS. 3, 4, 7 and 8 and, similarly, are intended to be part of the claimed invention.

All of the broken lines inside the perimeter of the circular broken lines shown in FIGS. 1, 2, 5 and 6 are part of the claimed invention and depict the actual appearance of the view within the density altitude reticle to show measurement symbols.

1 Claim, 6 Drawing Sheets
